UNITED STATES PATENT OFFICE.

SYLVANUS D. LOCKE, OF BRIDGEPORT, CONNECTICUT, ASSIGNOR TO LOCKE STEEL BELT COMPANY, OF BRIDGEPORT, CONNECTICUT, A CORPORATION OF NEW YORK.

CHAIN-MAKING MACHINE.

1,107,809.

Specification of Letters Patent. Patented Aug. 18, 1914.

Application filed June 4, 1903, Serial No. 436,711. Renewed January 17, 1914. Serial No. 812,628.

To all whom it may concern:

Be it known that I, SYLVANUS D. LOCKE, a citizen of the United States, residing at Bridgeport, in the county of Fairfield and State of Connecticut, have invented certain new and useful Improvements in Chain-Making Machines, of which the following is a specification, reference being had therein to the accompanying drawings.

10 This invention relates to improvements in machines for making chain links, more particularly to a machine for making drive chain links from sheet metal. It is an improvement upon the machines shown, described and patented in Letters Patent of the United States No. 580,564, to Viellard and Osswald, patented April 13th, 1897; No. 580,579 to S. D. Locke, patented April 13th, 1897; and No. 633,871 to S. Skogse, patented 20 September 19th, 1899.

One of the objects of my invention is to provide in a chain machine of the class described, a pitch correcting or sizing device for correcting the pitch of the links and 25 making the links uniform in size.

Another object of my invention is to provide in such a machine a simple and accurate gage for positioning and centering the strip of sheet metal to be acted upon relative 30 to the scoring chisels and forming elements of the dies.

Another object of my invention is to provide such a machine with an improved link extracting device, positively actuated and of 35 simple construction.

Another object of my invention is to provide such a chain making machine with scoring knives or chisels arranged to impart 40 lines of score longitudinal of the strip of metal and parallel except near their rear ends, where they diverge slightly for the purpose of providing at the small end bar of the links sufficient clearance to facilitate the coupling of the small end bar to the next 45 link of the series.

Other objects of my invention will be obvious from the drawings and description of a machine herein chosen for the purpose of illustration.

50 Figure 1 is a front view, partly in section, of a machine embodying my improvements. Fig. 2 is a view, partly in side elevation and partly in section, of the strip feed mechanism on the machine. Fig. 3 is a front view

of a portion of the strip feed mechanism, 55 detached. Fig. 4 is a front view of the forming dies, extracting mechanism, and sizing mechanism. Fig. 5 is an enlarged view of the dies, showing them in section, with a strip of metal between them; the sizing 60 mechanism is also shown. Fig. 6 is an edge view of a strip of metal in process of formation into a chain, some formed and coupled chain links being shown. Fig. 7 is a plan view of the metal strip and chain shown in 65 Fig. 6. Fig. 8 is a bottom plan view of the movable die and stretcher mechanism. Fig. 9 is a top plan view of the stationary die. Fig. 10 is a bottom plan view of a section of the strip of metal, showing the scoring. Fig. 70 11 is a perspective view of a completed link. Fig. 12 is a section on the line 12—12, of Fig. 13, illustrating a part of the extracting mechanism. Fig. 13 is a plan view of a portion of the extracting mechanism. Fig. 14 75 is a section on the line 14—14, Fig. 13. Fig. 15 is a front view of the metal strip guide, detached. Fig. 16 is a front view of a modified form of metal strip guide, detached. Fig. 17 is a vertical central section illustrating 80 the use of the modified type of strip guide on the die holder 39.

In the drawings—1 indicates as an entirely the main frame of the machine comprising uprights 2, 3, and a bed 4 arranged 85 between the uprights.

5 is a vertically reciprocatable slide mounted to move up and down in guides 6, 7, on the main frame.

8 is a main drive shaft transversely 90 mounted in bearings at the upper end of the frame. 9 is a countershaft transversely mounted upon the main frame and extending from one side to the other thereof. At one side of the main frame the counter 95 shaft carries a loose pulley 10, a fast pulley 11, and a fly wheel 12. At the other side of the frame the said counter shaft has mounted loosely upon it a pinion 13 carrying one element 14' of a clutch 14, the other element 100 14" of which is splined to the countershaft 9. Any suitable mechanism may be employed for throwing the longitudinally movable element 14" of said clutch into and out of engagement with the element 14', so as to 105 transmit power through the pinion 13. 15 is a gear wheel rigidly secured to said main shaft and in mesh with the pinion 13.

16 is an eccentric on the main shaft 8 connected by eccentric straps 17, 17', and pitman 18 to the slide 5.

As the construction of the press in itself forms no part of my invention, any well known type of press having a reciprocatable slide and a bed or bolster beneath it may be readily adapted to operate the chain link forming and assembling mechanism to be hereinafter described, and no further description of the press shown in the drawings is deemed necessary, as this particular press has been chosen simply for illustrative purposes and not in any limiting sense.

15 Any suitable mechanism may be attached to the press for feeding the stock or strip of metal from which the chain links are to be formed across the bed or bolster of the press. For the purpose of illustration I have, in 20 the drawings, shown a feed mechanism of which 19 is a bracket secured to the standard 3 of the frame and having a horizontally disposed platform 20, the inner end of which extends into a hole 3' through the 25 standard 3.

21, 21, are side walls extending vertically upward, one at each side of the platform 20. 22 is a horizontally reciprocatable slide suitably mounted at either side in guideways in the said side walls 21. It rests upon a horizontally disposed friction plate 23 having downwardly extending pins 24, 24, each surrounded by a coil spring 25 bearing at its upper end against the plate 23 and at 35 its lower end against the platform 20 so as to provide a yielding support for the slide 22 which normally tends to press the slide against the upper walls of the guideways to insure the closing of the feed jaws, to be hereinafter described, before the slide commences to move forward.

40 26 is a gripping piece carried by the slide 22, having an upwardly turned jaw 26' adapted to engage the under surface of the 45 stock or strip of metal to be fed across the bed or bolster.

27 is an oscillatable gripping dog having a jaw 27' adapted to engage the upper surface of the strip of metal to be fed, at a 50 point directly above the gripping jaw 26'. This gripping jaw 27 is pivotally mounted between upwardly extending lugs or ears 22', 22', on the slide 22, and carries an upwardly extending arm 28.

55 29 is a bell crank lever pivotally connected at 29' between the side walls 21 of the platform 20.

30 is a rod pivotally connected at 30' to the upper end of the arm 28, and at 30' to 60 the free end of the arm 29a of the bell crank lever 29.

31 is an adjustable stop for limiting the throw of the arm 28 in clockwork direction. This stop preferably consists of a screw extending through a threaded opening in a

cross bar 22*, which latter extends between the ears 22', 22', on the slide 22.

32 is a crank disk carried by the main shaft 8 and having a crank pin 32' to which is pivotally connected one end of a connecting rod 33, the other end of which is suitably connected to the free end of the arm 29b of the bell crank lever 29.

34, 34, and 35, 35, are straightening rolls for the strip of metal or stock. These rolls are horizontally disposed and suitably mounted between the side walls 21, 21 on the platform 20. A strip of metal, indicated by 36, is directed between the rolls 34, 34, and 35, 35, and between the gripping lips 26' and 27'. The dog 27 and arm 28 are shaped and proportioned to have a slight, rocking motion relative to the slide 22, so that in normal operation, as the connecting rod 30 is drawn to the right in Figs. 1 and 2, the gripping jaw 27' is rocked out of engagement with the upper surface of the strip of metal 36. The arm 28 then engages the stop 31 and the slide 22 recedes with the connecting rod 30. Upon the reversal of travel of the rod 30, it rocks forward the upper end of the arm 28 and causes the gripping jaw 27' to engage the upper surface of the strip 36, thereby gripping the said strip firmly between the jaws 26' and 27', and the slide 22 and strip 36 are together fed forward.

As the dies or forming elements for striking up and forming each chain link from a strip of metal, and coupling it to the next preceding link form no part of my invention, any suitable dies or forming elements for this purpose may be employed. In the drawings I have shown the use of two rigid dies for this purpose, which, in my opinion, were the invention of Herman Osswald of Brooklyn, New York, and to the invention of which I make no claim.

37 is a carrier or holder for the movable die, it being suitably connected to the slide 5.

28 represents as an entirety the movable die, it being suitably seated and held in the holder 37.

39 represents a bolster or die bed for the stationary die. It is detachably secured to the bed 4 in any suitable manner.

40 represents as an entirety a stationary die suitably secured in the die bed 39.

The dies 38 and 40, which coöperate with each other to form and assemble the links, are arranged in longitudinal alinement with the line of feed of the strip 36 and are properly centered relative to the said line of feed.

41, 42, are scoring knives or chisels embodying my invention and arranged at the right hand end of the movable die 38 and adapted to impart lines of score to the upper surface of the strip of metal, which lines are parallel in the direction of the feed of the said strip with the exception of a slight diver-

gence at their right hand ends. The divergence from parallelism of the right hand ends of the chisels is indicated at 41', 42', and is for a purpose to be hereinafter described. 43, 44, are corresponding scoring knives or chisels carried by the stationary die 40 and arranged to impart lines of score to the under surface of the strip of metal, each of which lines is directly beneath a line 10 of score imparted by one of the upper scoring knives. At their front ends, each of the scoring knives or chisels 43, 44, is preferably bent or curved inwardly, as indicated at 41", 42", respectively. Preferably, these front 15 ends of the scoring knives are curvilinear in shape and extend inwardly and rearwardly, for a purpose to be hereinafter described.

Of the dies 38 and 40, 45 is a severing and crimping element on the upper die having a 20 convex crimping surface. It is arranged to cooperate with a cutting and bending knife 46 on the lower die. The lower die is recessed at 47 in front of the cutting knife 46 and beneath the severing and crimping element 45. The metal of the stationary die 40 in front of the recess 47 is cut away along the inclined line 48 to permit a section of the metal of each link blank to be bent downwardly by the severing and crimping element 45 before it has been severed at one end by the combined action of this element and knife 46.

49 is a curved forming or crimping element on the movable die 38, about which the 35 metal for forming the smaller end bar or pintle of each link is bent or crimped. In front of this former 49 is a recess 50, and in front of it is an irregular shaped end bar forming punch element 51 consisting of 40 two substantial quarter circles 51', 51". 52 is a forming and bending projection on the stationary die, it being adapted to enter the recess 50 in the movable die.

52' is a shoulder on the projection 52 45 adapted to fold or crimp the metal for the small end of the link against the curved end of the element 49 on the movable die. 53 is a scoring knife on the stationary die 50 adapted to impart a transverse score to the strip of metal along the line of severance of two links which are to adjoin each other and in conjunction with the forming corners 52', 52", is adapted to force the metal of the link to follow the quarter circles 51', 51", on the former 51. This scoring knife 53 is in vertical alinement with the line of intersection of the said two quarter circles of the punch element 51. In advance of the said punch element 51 the movable die is recessed as indicated at 54 to allow clearance for the free upturning of the long lip of the metal blank for a link, which at this step of its formation projects upwardly from the metal strip. At 56 the stationary die is recessed to receive a cutting or severing knife 57 on the

movable die, the edge 56' being a knife edge to work in conjunction with the knife 57 to sever the metal strip. Immediately in front of the cutting knife 57, the movable die is shaped as indicated at 58 to complete the rounding and formation of the small end bar of each link in coöperation with the recessed section 59 of the stationary die. At 60 the movable die is recessed for the purpose of engaging the longer section or lip 61 of metal turned up from the central portion of each link blank and bending, curling and conforming it to the cylindrical shape desired, at the same time causing it to encircle the small end bar or pintle of the link in front of it, thereby coupling or attaching these links together. The stationary die is recessed at 61 to coöperate with the recessed portion 60 of the movable die in the final shaping and forming of the large end 65 bar of each link.

62 is a projection extending transversely across the recessed portion 61 of the stationary die. It serves to prevent the ends of the lips of metal forming the large end 66 or sprocket bar of each link from engaging with each other, and to space them apart a predetermined distance.

Heretofore some difficulty has been experienced in feeding the strip of metal centrally between the dies, in such manner that the scoring knives and forming elements will act to form links symmetrical on either side of their longitudinal axis, that is, with side bars of substantially the same width and uniformly spaced from said longitudinal axis of the links. This difficulty I have overcome by attaching a strip gage or feed gage between the feed mechanism and the dies. In the drawings it is indicated as an 95 entirely by 64. It preferably consists of a bar of metal arranged transversely on the stationary die holder 39, and suitably secured in position adjacent to the right hand end of the stationary die 40. In the top of 100 this piece of metal is cut a V-shaped groove 65 with the axis of the V. in the vertical central longitudinal plane of the dies. The walls of this V-shaped groove are preferably elevated somewhat above the horizontal 115 plane of the stationary die and the width of the V-shaped groove at its middle vertically is preferably of the width of the standard size strip to be used with the set of dies to which the gage is attached. The taper of 120 this gage allows for variation in width of the strip of metal 36, so as to insure the proper centering of the strip despite its variation in width.

It is essential that some means be provided for extracting the links from the dies after they have been completely formed and for delivering them, one after the other, from the machine. Of my improved extracting mechanism, 66 is a chain guide 130

comprising two bars 66', 66", rigidly secured at their inner ends to the die bed 39; and projecting into the opening 3* through the adjacent wall of the main frame of the machine. These bars are longitudinally grooved and recessed, as indicated at 67 to constitute a guideway for the chain. The bars are recessed at 66" to receive a swingable cover plate 68 which is pivotally connected at 69 between upwardly projecting ears 66* on the said guide bars.

68' is a thumb nut extending through a slot 68* in the cover plate 68 and detachably fitted into the guide bar 66", for the purpose of holding down the cover plate 68 under normal conditions.

70 is a sprocket wheel arranged between and projecting between the guide bars 66', 66". It is carried by a shaft 71 mounted in bearing blocks 72, each detachably secured to one of the aforesaid guide bars.

73 is a pawl carrying arm loosely mounted on the shaft 71.

74 is a pawl pivotally connected to the arm 73.

75 is a ratchet wheel rigidly secured to the shaft 71 and having its teeth in the plane of the pawl 74.

76 is a lug or projection carried by the slide 5. It is pivotally connected at 76' to a rod 76", the lower end of which is pivotally connected at 76" to the arm 73.

77 is a spring having one end secured at 77' to the frame of the machine, and its other end bearing against the teeth of the sprocket wheel 70 to offer a frictional resistance to the rotation of the latter.

In the manufacture of chain from sheet metal in which the end bars of the links are formed by rolling up a section of metal, variation in pitch of the link is quite certain to arise, due to the variations in thickness of the metal stock. In all drive chains made from sheet metal of which I am aware, and in which the links are formed in dies, the outside dimensions of the end bars as curved or rolled up by the dies, are substantially uniform. The inside dimensions, however, of the large end or sprocket bars of each link, which encircle the small end bar of an adjoining link, vary in accordance with the thickness of the metal. Consequently, the thicker the metal the shorter the chain and the thinner the metal the longer the chain. This being the case, I have found it essential to employ a device for correcting the pitch of the link and making it uniform throughout the chain. If a series of links is subjected to a stretching action in order to make the pitch length of the series correct, there is no assurance that the individual links of the series will be of the proper pitch; some links will be of longer pitch than others. I have, therefore, found it desirable to subject each link

individually to a sizing and correcting device, preferably while the link is still in the machine, so as to insure uniformity of pitch of the link irrespective of variation in thickness of the stock of metal. Such a sizing or pitch correcting device is indicated in the drawings as an entirety by 78 and is arranged to operate simultaneously with the link forming dies, thus avoiding a separate operation outside of the machine for the sizing and correcting of the pitch of the links. Of this sizing or pitch correcting device 78, 79 is an arm extending forward from and preferably detachably secured to the die holder 37. This arm 79 has formed, preferably integrally with it, a downwardly extending finger 80 which is pointed at its lower end as indicated at 81, the rear surface 81' of the said pointed finger being shorter than and at a greater inclination to the horizontal than the front surface 81" of the said finger. This finger 80 is arranged to enter the sprocket opening in the last link but one of the links formed in the machine.

82 is a block or finger pivotally connected at 82' in the bifurcated end of the arm 79. This block or finger extends downwardly beneath the arm 79, as indicated at 82" and is adapted to enter the sprocket opening in the link next preceding the link entered by the finger 80.

83 is an adjustment screw fitted in the finger 82 and adapted to extend on the rear side of the latter and bear against the arm 79. Its purpose is to adjust the said finger 82 about the axis of the pivot 82' and toward or from the finger 80. The adjustment wheel 83' for the screw 83 has a toothed or serrated periphery 83".

84 is a lock pawl extending through an opening in the forward projection 82" of the finger 82, and engaging with the periphery of the thumb wheel 83' to hold the wheel at any point of adjustment.

85 is a spring bearing at one end against the lock pawl 84 and having its other end secured at 85' to the finger 82. The distance between the front wall of the downward extension 82" of the finger 82 and the rear wall of the finger 80 remains substantially constant when the machine is in operation. If a link is shorter in pitch than it should be, these sizing fingers bring it up to proper pitch by stretching it. In practice, I have found it desirable to form and arrange the dies 38 and 40 for making of the desired and proper pitch, chain links from the thinnest sections of the strip of steel used, depending upon the stretcher or pitch correcting device 78 to draw the links formed from the thicker sections of the strip of metal up to gage.

By employing with a set of forming dies a sizing and pitch correcting device such

as just described, not only is a separate operation outside the machine with the forming dies obviated, but as the pitch of each link is corrected immediately after the formation of the link, it is possible to check up the operation of the machine quickly, in order to insure that the links formed by it at any time, are standard. This checking may be done at any instant during the operation of the machine, and in the event that it is found that the links are not of proper pitch, the adjustment of the attachment 78 or the dies to make them so can be readily and quickly made before much material has been spoiled.

The operation of the machine will be readily understood. A strip of metal 36 is directed through the feed mechanism until the gripping jaws 26', 27', of the feed mechanism can engage with it. Power is then applied through the countershaft 9 to actuate the feed mechanism and slide 5. The strip 36 is guided and centered by the gage 64 so as to lie properly between the dies 38 and 40. When the slide 5 descends the scoring knives 41, 42 on the slide impart to the upper surface of the strip of metal lines of score 80, 81, as indicated in Fig. 7, and the scoring chisels 43, 44, on the stationary die bed impart to the under surface of the strip of metal lines of score 82, 83, as indicated in Fig. 10. When the slide next ascends, the feed mechanism feeds forward the strip of metal one step and the first forming elements of the dies operate on the strip. The strip is fed forward step by step at each elevation of the slide, the dies operating on each link blank to form a completed link. After the first completed link has been formed, the operator extracts it from the dies and positions it to be coupled to the next succeeding link. The operator continues to extract and advance the links thus formed and coupled together until the first one of said links is engaged by a tooth on the sprocket wheel 70. Thereafter the extracting mechanism operates to automatically extract the chain links from the dies and advance them one step at a time.

With the particular set of forming dies illustrated in the drawings, I have found it advisable to have the extracting mechanism operate to draw the last formed link forward so that its small end bar is slightly in front of its proper position to be coupled to the next link to be formed. This is done in order to facilitate the proper forward feed of the metal strip for operation upon it by the forming elements which complete the forming of a link. As the slide descends after the last formed link has been extracted by the extracting mechanism, the inclined surface 81' of the pitch correcting finger 80 engages the large end bar of said link and presses the link rearwardly until its small

bar is properly centered relative to the final link forming elements of the dies. The pitch correcting or sizing fingers 80, 82', operate at each descent of the slide to enter two coupled links in the chain guide 66 and stretch the links up to gage, if required.

It is generally understood that, in rolled or drawn metal, such as is employed in the making of sheet metal drive chain links, fibers of the metal arrange themselves longitudinally of the strip of metal, or parallel to the direction in which the metal passes through the rolls or is drawn. It is believed that this fibrous nature of the metal is, to a certain extent, responsible for the tendency of the metal of which the end bars of the links are formed, to crack or tear away from points at the ends of the lines of scoring for the side bars in all the earlier known forms of sheet metal drive chain links. At any rate, and for example, in many sheet metal links of the general construction shown in Letters Patent of the United States, No. 633,371, to G. Skogse, patented September 19th, 1899, after the metal of the end bars is bent or curved into final shape, cracks in the metal are noticeable leading from the ends of the lines of scoring. Where this is the case, and the link is subjected to a tensile strain, the end bars are liable to tear out or shear commencing at the said crack. By scoring the metal of the link transversely from the ends of the longitudinal lines of score for the side bars, which latter scores extend substantially in the lines of arrangement of the fibers of the metal, I overcome the tendency of the metal of the end bars to crack or tear along the line of fibers at the ends of the side bar scoring, as it is bent or curved into shape. At the same time, by said transverse scoring, the fibers of the metal are so disarranged at the end of the longitudinal scoring and immediately in line therewith, that no sharp corner exists between the metal of the end bar and the metal of the side bar and a fillet 85 is formed to strengthen the link at this point. In fact, the corners between the end and the side bars of my improved link are built up or filled in instead of being sharply defined substantially right angle corners, as has been the case with all earlier sheet metal drive chain links of which I am aware. When a tensile strain is applied to one of my improved links, no sharply defined corners exist between the end bars and the side bars where the transverse scoring is done, and from which the end bar will readily tear out. This transverse scoring of the metal at the ends of the longitudinal lines of score, furthermore, substantially overcomes the tendency of the metal of the end bars to crack or tear away from the side bars under the bending or curling up operation incident to the final shaping of the end bars, as well as

the tendency of the metal to shear or tear along the lines of scoring which are substantially in line with or parallel to the lines of application of strain on the link. The divergence at the rear end of each link of the lines of scoring for the side bars, tends to increase the distance between the side bars of the link adjacent to the small end bar in order to provide sufficient clearance for facilitating the formation of the long narrow lip of the large end bar for the next succeeding link about the small end bar or pintle. Heretofore, so far as I am aware, this necessary clearance between the side bars at the small end bar of the link has been obtained by scoring the link blank on lines which diverge from each other throughout their entire length, as illustrated in the said Skogse patent hereinbefore referred to. Where the lines of score for the side bars thus taper throughout their entire length, the sprocket opening through the link is of uneven dimensions and the side bars of the link do not run uniformly relative to the sprocket wheel. Furthermore, where a relatively narrow side bar is required to begin with, the said taper scoring tends to weaken the side bar more than is advisable. Again, where chain having its links thus taper scored is used on a horizontal drive over small sprocket wheels and the lower run of the chain is active, the upper run may sag sufficiently to engage with the links of the lower run and have one of the narrow lips of the large end bar of a link on the upper run enter the opening of and become wedged in one of the links of the lower run with resultant damage and stoppage of the machine. I have found that the only place where clearance for the narrow lip of the large end bar is required, is immediately adjacent to the small end bar of the link with which the said narrow lip is coupled, consequently the slightly diverging scoring adjacent to the small end bar of one of my improved links, accomplishes all of the desired results and obviates the difficulties and disadvantages of the earlier taper scoring for the side bars.

In the majority of instances the strips of metal used in these machines is of sufficient thickness to insure that the part of the strip being acted upon by the dies will spring up away from the stationary die as the movable die is elevated. The V-shaped gage 64 is raised above the stationary die so as to require a slight bending downward of the strip of metal as the dies come together. Where, however, the strip of metal is quite thin and does not possess sufficient spring action to insure that its free end will spring up away from the stationary die when the movable die is elevated, I have found it advisable to slightly change the position of the V-shaped gage and to provide a strip lifting

element between it and the dies. This modified construction is illustrated in Figs. 16 and 17. 86 is a block of metal detachably secured to the die bed 39. It has formed in it an inverted V-shaped groove 87, which groove at its horizontal center, is substantially the standard width of the strip of metal to be fed to the dies. In front of this gage 86 the metal of the die bed is vertically recessed, as indicated at 88, to receive a spring pin 89 which is normally pressed upwardly by a spring 90. The operation of this modified gage and spring pin will be readily understood. The strip of metal 36 is directed through the gage and over the spring pin 89, which latter bears against the under surface of the strip and normally presses it upwardly into the gage. After each working stroke of the slide as it is elevated, the spring pin 89 presses the free end of the strip of metal upwardly and away from the stationary die and also presses the strip of metal against the walls of the V-shaped groove 87, so as to insure that the strip will be properly centered as it is fed forward step by step.

Many alterations in the construction, and many apparently widely differing embodiments and applications of my invention will suggest themselves to those skilled in the art of making sheet metal chain links and chain making machines, without departing from the scope and spirit thereof. My disclosures and description herein are purely illustrative, and are not intended to be in any sense limiting.

While in the drawings, transverse scoring at the ends of the longitudinal lines of score is shown only on the under side of the metal strip 36 when it is in the machine and at the front end of the link blank, similar transverse scores may be made in both surfaces of the link blank and at both ends of the longitudinal lines of score. I have found, however, in practice, that this transverse scoring at the ends of the links whereby the large end bars are formed and only on one surface of the link blank, is sufficient to effect the desired results.

The cover 68 for the chain guide is preferably hinged in order to facilitate access to the interior of the guide for the purpose of directing chain over the sprocket wheel 70.

What I claim is—

1. In a machine of the class described, the combination with means for transforming a strip of metal into a series of connected chain links, of devices arranged adjacent to said strip transforming means for successively correcting the pitch of each link as it is completely formed.

2. In a machine of the class described, the combination with means for transforming a strip of metal into a series of con-

- connected chain links, of devices for simultaneously correcting the pitch of formed links during the formation of other links. 65
3. In a machine of the class described, the combination with means for transforming a strip of metal into a series of connected chain links, of devices for correcting the pitch of the links immediately after their formation and before they leave the machine. 70
4. In a machine of the class described, the combination with a stationary die and a movable die adapted to transform a strip of metal into a series of connected links, of a device movable with said movable die for correcting the pitch of the formed links. 75
5. In a machine of the class described, the combination with a stationary die and a movable die adapted to transform a strip of metal into a series of connected links, and a holder for said movable die, of a device carried by said holder for the movable die for correcting the pitch of the formed links. 80
6. In a machine of the class described, the combination with a stationary die and a movable die adapted to transform a strip of metal into a series of connected links, and a holder for said movable die, of a pitch correcting device for the formed links carried by said holder for the movable die and comprising two fingers, one adapted to be projected through the opening in one formed link, and the other adapted to be projected through the opening in the next formed link in the series. 85
7. In a machine of the class described, the combination with a stationary die and a movable die adapted to transform a strip of metal into a series of connected links, and a holder for said movable die, of a pitch correcting device for the formed links carried by said holder for the movable die and comprising two fingers, one adapted to be projected through the opening in one formed link, and the other adapted to be projected through the opening in the next formed link in the series, and means for adjusting one of said fingers relative to the other. 90
8. In a machine of the class described, the combination with means for transforming a strip of metal into a series of connected chain links, of a rotary device for positioning the links between the dies and for extracting the formed links from said transforming means, and means for actuating said rotary device. 95
9. In a machine of the class described, the combination with a set of dies, one movable and the other stationary, adapted to transform a strip of metal into a series of connected chain links, of a rotary device for positioning the links between the dies and for extracting the formed links from between said dies, and means for actuating said rotary device simultaneously with the movements of said movable die. 100
10. In a machine of the class described, the combination with a set of dies, one movable and the other stationary, adapted to transform a strip of metal into a series of connected chain links, of a rotary device for positioning the links between the dies and for extracting the formed links from between said dies, a reciprocatable holder for said movable die, and means connecting said reciprocatable holder and said rotary device to actuate the latter simultaneously with the movement of said movable die. 105
11. In a machine of the class described, the combination with a set of dies, one movable and the other stationary, adapted to transform a strip of metal into a series of connected chain links, and a reciprocatable holder for said movable die, of a sprocket wheel arranged to engage the formed links one after another for positioning the last formed link between the dies and extracting the formed links step by step away from said dies, and actuating mechanism for said sprocket wheel connected with said reciprocatable holder and actuated thereby. 110
12. In a machine of the class described, the combination with a set of dies adapted to transform a strip of metal into a series of connected chain links, of a guide for the formed links, a sprocket wheel arranged to engage the formed links one after the other for positioning the last formed link between the dies and extracting the formed links step by step through the said guide, and means for actuating said sprocket wheel. 115
13. In a machine of the class described, the combination with a set of dies adapted to transform a strip of metal into a series of connected chain links, of a guide for the formed chain links, the said guide being formed with a hinged cover portion to permit the positioning of the formed links along the guide, a sprocket wheel projecting into said guide for positioning the last formed links between the dies and for extracting the connected chain links from the dies, and means for actuating said sprocket wheel. 120
14. In a machine of the class described, the combination with a set of metal shaping and forming dies, and a feed mechanism for a strip of metal, of a gage for centering the strip having a V-shaped groove with the walls of which the edges of the metal strip engage. 125
15. In a machine of the class described, the combination with a set of metal shaping and forming dies, and a feed mechanism for a strip of metal, of a gage for centering the strip arranged between said dies and said

feed mechanism and having a V-shaped groove with the walls of which the edges of the metal strip engage.

16. In a machine of the class described, the combination with stationary and movable shaping and forming dies and a feed mechanism for a strip of metal, of a stationary gage for centering the strip arranged between said stationary die and said feed mechanism and having a V-shaped groove with the walls of which the edges of the metal strip engage.

17. In a machine of the class described, the combination with stationary and movable shaping and forming dies and a feed mechanism for a strip of metal, of a stationary gage for centering the strip arranged between said stationary die and said feed mechanism and having a V-shaped groove with the walls of which the edges of the metal strip engage, and a spring pin arranged between said stationary die and said centering gage and adapted to normally press the strip of metal upwardly against the walls of said V-shaped groove in the gage.

18. In a machine for making chain links from sheet metal, the combination with a set of link forming and shaping dies, of scoring knives arranged forward or in front of the forming and shaping dies and parallel to each other except at their rear ends where they diverge slightly from each other.

19. In a machine for making chain links from sheet metal, the combination with a set of link forming and shaping dies, of scoring knives arranged forward or in front of the said link forming and shaping dies for longitudinally scoring the strip of metal at either side thereof, and having curved ends to transversely score the strip of metal.

20. In a machine for making chain links from sheet metal, the combination with a set of link forming and shaping dies, of scoring knives arranged forward or in front of the said link forming and shaping dies for longitudinally scoring the strip of metal at either side thereof, and having their front ends curved to transversely score the strip of metal, and their rear ends diverging slightly relative to each other.

21. In a machine of the class described, in combination with a set of link forming and shaping dies, of scoring knives arranged for-

ward or in front of the said link forming and shaping dies and in alignment with each other, and having curved ends, said scoring knives being adapted, one to score a link blank on its under surface on a longitudinal line with a curved end extension, and the other to similarly score the upper surface of the link blank.

22. In a machine of the class described, the combination with means for transforming a strip of metal into a series of connected chain links, of a guide for the formed links rigidly supported adjacent to the link forming mechanism, said guide comprising upper and lower walls and the lower wall being formed with a longitudinal opening therein, and rotary extracting mechanism projecting through said opening to move the chain links.

23. In a machine of the class described, the combination with means comprising a stationary die, and a movable die, for transforming a strip of metal into a series of connected chain links, a guide comprising upper and lower walls carried by the stationary die, rotary extracting mechanism mounted in said guide for positioning the last formed link between the dies and for moving the chain links away from the dies and connections between said extracting mechanism and the movable die actuating the said extracting mechanism.

24. In a machine of the class described, the combination with means, including a stationary die and a movable die, for transforming a strip of metal into a series of connected drive links, of devices for correcting the pitch of said links successively, the said devices being arranged adjacent to the said strip transforming means and controlled by the movable die thereof and comprising a pair of fingers arranged to enter two adjoining links after they are formed, the rear wall of the finger immediately adjacent to said strip transforming means being inclined and arranged to engage the large end bar of the adjacent link.

In testimony whereof I affix my signature, in the presence of two witnesses.

SYLVANUS D. LOCKE.
